UNITED STATES PATENT OFFICE

169,778

COFFEE BREWER

Fred E. Newman, Chicago, Ill.

Application November 17, 1952, Serial No. 22,322

Term of patent 14 years

(Cl. D44—26)

To all whom it may concern:

Be it known, that I, Fred E. Newman, a citizen of the United States, residing at Chicago, in the county of Cook and State of Illinois, have invented a new, original, and ornamental Design for a Coffee Brewer, of which the following is a specification, reference being had to the accompanying drawing, forming a part thereof, in which:

Fig. 1 is a side elevational view of a coffee brewer showing my new design, the view from any side being the same;

Fig. 2 is a top plan view thereof, and

Fig. 3 is a bottom plan view thereof.

I claim:

The ornamental design for a coffee brewer, substantially as shown and described.

FRED E. NEWMAN.
